UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

LAMP.

SPECIFICATION forming part of Letters Patent No. 642,527, dated January 30, 1900.

Application filed September 2, 1899. Serial No. 729,306. (No model.)

To all whom it may concern:

Be it known that I, FRANK RHIND, a citizen of the United States, residing at Bridgeport, Connecticut, have invented a new and 5 useful Improvement in Lamps, of which the following is a specification.

My invention relates chiefly to lamps such as are used on cycles and other vehicles and especially to those adapted to burn acetylene or other gas. It is intended to render such lamps more efficient and convenient.

In the accompanying drawings, Figure I is an elevation of a cycle-lamp embodying my invention. Fig. II shows a substituted 15 portion. Fig. III shows a modification.

1 designates a lamp-body provided with screw-threaded portion 11 and locking-collar 12; 2, a connecting-shell threaded at 21 and provided with stuffing-box 22 and bead 23; 20 3, a gas-tube having a head 31 and handle 32; 4 40 burner-tips; 5, a guard-shell; 6, a reflector; 7, a wind-guard; 8, Fig. II, a lamp-top provided with locking-flange 81; 61, a pivot-pin; 71, a sleeve; 72, a set-screw, the 25 last three parts being only found in Fig. III.

In the example of my invention shown in Fig. I the lamp-body 1 may be of any desired form. As shown, it is provided with an upwardly-projecting internally and externally 30 threaded portion 11, into which a burner-tip 4 is secured. Detachably engaging with the exterior thread of the portion 11 is a shell 2, open to pass freely over the burner 4 and having at its upper end a stuffing-box 22. A 35 guard-shell 5 is secured on the shell 2 at its upper end and at its lower end engages with the collar 12. It is preferably rotatable on the shell 2, so as not to interfere with the screwing of the shell 2 on the portion 11. Rotatable and gas-tightly secured in the stuffing-box 22 is the gas-tube 3, whose head 31 is laterally pierced to receive a second burner-tip 40. A reflector 6, shown as conical, is suitably secured to the head 31. To the open 45 outer end of the reflector 6 is secured a wind-guard 7, shown as a short perforate cylinder.

The operation of the device will be readily understood from an inspection of the drawings. It is clear that the gas generated in 50 the body 1 will pass through the tip 4, shell 2, gas-tube 3, and tip 40, where it may be lighted.

It is also clear that the burner 4 may be removed, if desired. By means of the handle 32 the gas-tube 3 and connected parts may be turned to throw the light in any desired 55 direction. This is found very convenient, either to protect the flame against a side wind or when a tire needs pumping or any slight repairs are necessary.

In practice it is found that a flame surrounded by an open reflector is quite easily blown out by the wind. I therefore secure to the free end of the reflector the perforate wind-guard 7, which serves to break up the air-currents and protect the flame. 60 65

In Fig. II of the drawings I have shown how the well-known closed lantern-top 8 may be substituted for the device shown in Fig. I, the flange 81 locking with the collar 12 on the body 1 by means of a bayonet-joint, as shown, 70 or in any desired manner. This substitution necessitates the consumption of a greater volume of gas to produce a given efficiency, but is desirable in very rainy or windy weather. 75

In Fig. III, I have shown a modified form 80 of perforate wind-guard adapted to afford a greater protection from either wind or rain than that shown in Fig. I. In this form the reflector may well be of substantially hemispherical shape and provided with a pivot-pin 61, as shown. The guard 7 is also substantially hemispherical and adapted to rotate on the pin 61 and the gas-tube 3. A sleeve 71, secured to the guard 7, rotatable on the tube 3 and provided with set-screw 72, permits the 85 securing of the guard 7 either in its operative position in front of the reflector 6, as shown, or behind and surrounding the reflector, as shown in dotted lines. It is clear that the guard may be set at any intermediate position—*e. g.*, so as to cut off a wind blowing across the path without so much obstructing the light. 90

It is understood that many mechanical alterations and changes of form may be made 95 without departing from my invention and that parts of my invention may be used separately—*e. g.*, the turning of the upper portion of the lamp to project the light in any direction is advantageous, whether or not 100 the lamp is supplied with a particular form of wind-guard. It is also understood that while

it is of the greatest practical advantage that the inner surface of the portion 6 should be polished or otherwise light-reflecting, the function of protecting the flame from wind 5 and storm would be subserved by any concave hood surrounding or inclosing the burner, so that when in the claims I use the word "reflector" I intend to include such a hood.

It is found in the practical use of acetylene-lamps upon cycles or other vehicles that it is impossible to maintain an even production of gas. Hence a flame such as would be used in the construction shown in Fig. I may vary greatly in length, at times extending to 15 three or four inches, or even more. For this reason the usual lens or other glass covering the outer end of the reflector is impracticable; but by the integral or unitary rotation of the burner and the open concave reflector which 20 surrounds and protects the flame the rider of a bicycle is enabled to temporarily protect the flame from a sidelong gust without seriously decreasing the effective lighting of the road. This integral rotation of the burner 25 and the reflector is particularly desirable where the flame is projected axially of the reflector to avoid destruction of the reflecting-surface.

What I claim is—

- 30 1. In a lamp an integrally-revolvble horizontally-disposed burner and reflector, substantially as described.
2. In a lamp an integrally-revolvble burner and open concave reflector, substantially as described.
- 35 3. In a lamp an integrally-revolvble horizontally-disposed burner and open concave reflector, substantially as described.
4. In a gas-lamp in combination a body, a 40 rotatable gas-conducting tube and a gas-burner and a reflector both mounted on said tube and revoluble therewith, substantially as described.
5. In a gas-lamp in combination a body, a 45 gas-conducting tube, a reflector mounted on said tube and a burner axially disposed within said reflector, said reflector and burner being adapted to revolve with respect to said body, substantially as described.

6. In a lamp a horizontally-disposed gas- 50 burner and a reflector having a horizontal axis surrounding said burner and adapted to protect the flame issuing therefrom, said burner and said reflector being adapted to revolve together around a common axis, sub- 55 stantially as described.

7. In a lamp in combination a body, a rotatable gas-conducting tube, a gas-burner and a reflector surrounding said burner and adapted to protect the flame issuing therefrom, said 60 burner and said reflector being mounted on said tube and revoluble therewith, substantially as described.

8. In a lamp in combination an open reflector and a perforate wind-guard at the free end 65 of said reflector, substantially as described.

9. In a lamp in combination an open reflector and an adjustable wind-guard at the free 70 end of said reflector, substantially as described.

10. In a lamp in combination an open reflector, an adjustable perforate wind-guard and means for securing said wind-guard either in or out of operative position, substantially as 75 described.

11. In a lamp in combination an open reflector, an adjustable perforate wind-guard and means for securing said wind-guard in any desired position, substantially as described.

12. A gas-generator-lamp body adapted to 80 have alternatively secured thereto a plurality of different burner-inclosing portions, substantially as described.

13. A gas-generator-lamp body provided with separate means for securing thereto a 85 plurality of different burner-inclosing portions, substantially as described.

14. In combination a gas-generator-lamp body, means for securing a burner to said body, means for attaching to said body a 90 burner-inclosing portion and separate means for securing to said body a gas-conveying portion, adapted to support a burner and a reflector, substantially as described.

FRANK RHIND.
